I. M. MATSON

FIRE EXTINGUISHER

Filed March 22, 1922

UNITED STATES PATENT OFFICE.

IVAN M. MATSON, OF CHICAGO, ILLINOIS.

FIRE EXTINGUISHER.

Application filed March 22, 1922. Serial No. 545,837.

To all whom it may concern:

Be it known that I, IVAN M. MATSON, a citizen of the United States of America, and a resident of Chicago, county of Cook, 5 and State of Illinois, have invented a new and useful Improvement in Fire Extinguishers, of which the following is a specification.

This invention relates to fire extinguishers 10 of that class intended to be thrown against burning objects, and thereby broken and releasing a fire extinguishing liquid. The object of the invention is to improve this type of fire extinguisher by providing for 15 the efficient spraying of the liquid when the container is broken.

The objects of the invention are accomplished by the device shown in the accompanying drawing, which represents in elevation 20 the improved extinguisher supported in a bracket which is shown partly in section.

The invention may be carried into effect 25 by means of any suitable fragile container such as a glass bulb, spherical or preferably gourd-shaped to provide a suitable handle, this bulb being partly filled with a fire extinguishing liquid such as carbon tetrachlorid, and having the air exhausted therefrom in the manner of an electric lamp. In the use of the device it is thrown against 30 burning surfaces, and thereby broken. The explosive effect due to the inrushing of air results in the effective spreading of the liquid and smothering of the fire.

A preferred form as illustrated in the drawings consists of a thin gourd-shaped glass container 1, having a bulbous body 35 part 2, and cylindrical handle 3 of less diameter than the part 2. The container is

sealed from the outer atmosphere at its ends 4 and 5 in the same manner as an electric lamp bulb. It is preferably about two-thirds filled with a fire extinguishing liquid such as carbon tetrachlorid, the surface of 45 which is indicated by the line 6. The air is exhausted from the space 7 above the liquid. The extinguisher is shown supported by a wall bracket 8 which encircles the handle 3.

In the use of the extinguisher it is broken 50 by being thrown against a burning surface. The explosive effect due to the inrush of the air into the space from which the air had been exhausted results in the liquid being widely spread, and therefore, utilized 55 to the maximum degree. The objection to the usual fire extinguisher of this general class is that when it is broken the liquid falls and is not utilized to the maximum degree, this being due to having no provision 60 for producing the explosive effect above described.

I claim:

1. A fire extinguisher comprising a fragile container partly filled with a fire extinguishing liquid, and the remainder of 65 the container having the air partially or completely exhausted therefrom.

2. A fire extinguisher comprising a glass container sealed from the outer atmosphere 70 and containing therein a liquid under less than atmospheric pressure.

3. A fire extinguisher comprising a gourd-shaped fragile container having a fire extinguishing liquid therein under less than 75 atmospheric pressure.

Signed at Chicago this 20th day of March, 1922.

IVAN M. MATSON.
